UNITED STATES PATENT OFFICE

WALTER D. TEAGUE, OF FOREST HILLS, NEW YORK, ASSIGNOR TO TURNER GLASS CORPORATION, OF TERRE HAUTE, INDIANA, A CORPORATION OF INDIANA

DESIGN FOR A BOTTLE OR SIMILAR CONTAINER

Application filed September 8, 1930. Serial No. 36,907. Term of patent 7 years.

To all whom it may concern:

Be it known that I, WALTER D. TEAGUE, a citizen of the United States, residing at Forest Hills, in the county of Queens and State of New York, have invented a new, original, and ornamental Design for a Bottle or Similar Container, of which the following is a specification, reference being had to the accompanying drawing, forming part thereof.

Fig. 1 is a horizontal section looking down, of a bottle or similar container showing my new design, the section being taken substantially on line 1—1 of Fig. 3.

Fig. 2 is a bottom plan of a bottle or similar container as shown in Figures 3 and 4.

Figs. 3 and 4 are elevations of a bottle or similar container showing my new design, the two figures being taken from slightly different view-points.

I claim:

The ornamental design for a bottle or similar container as shown.

WALTER D. TEAGUE.
